UNITED STATES PATENT OFFICE.

JOSEPH MOSES WARD KITCHEN, OF EAST ORANGE, NEW JERSEY.

METHOD OF AND MEANS FOR PREPARING FUELS.

No Drawing. Application filed November 9, 1923. Serial No. 673,828.

The general object of this invention is securing economy in the use of fuels thru the preparation of crude fuels for various purposes such as generating gas, fire kindling, heating, and other purposes. In carrying out the general purpose, I utilize with good advantage, crude fuels and low cost carbonaceous matters that are not used at all, or not used with advantage in their physical condition. The basic idea of the invention is to carbonize fuels rich in volatile solvents, and thus more or less harden those fuels thru their coking, by application of heat of various temperatures; and utilizing as burnable gas the volatile driven off in the coking. After securing the coke as a basis for fuel, I reconstitute in the coke, either in its fuel particles or in the fuel-mass, varying amounts of volatile, to give the fuel a greater intensity of heating power than what would be possessed by the hardened fuel if used alone. An essential part of the invention is to secure a sufficiently permanent porosity of the fuel-mass so that when the fuel-mass is being burned or heated, the crumbling and compaction of the fuel will be prevented which occurs in crude soft fuels under the solvent action of the volatile content in those soft crude fuels when subjected to heat in the fuel-mass, or in atmospheric exposure.

In my copending applications, Ser. Nos. 298,275; 295,513; 353,106; 522,920; and 625,025, I describe and claim various methods of preparing such fuels and burning or gasifying them. The present application relates in part and in particular to a method of impregnating coke with low cost petroleum fractionates, the penetrative impregnating character of which is increased, or produced, by subjecting such hydrocarbon impregnants to heat of various degrees of intensity before their use as impregnants.

The invention relates to methods for controlling the amount of heat applied in increasing the liquidity of such impregnants, which is an important matter, on account of the relatively quick volatilizing character of such impregnants; and hence, the danger of their ignition during the preparation of the fuels.

The invention comprises a selection of the character of the coked materials used for the various applied purposes; and includes the temperatures applied in the carbonization of the selected materials. Coke pro-

duced by high temperature carbonization, is very hard and vitreous in character, and has slight inflammability; but that character renders such high temperature cokes 60 resistant to the gasifying heat of gas making processes, sufficient in degree to volatilize and gasify hydrocarbon impregnants absorbed into the porosities of coke of that resistant character. Coke of that kind if 65 impregnated by the method of the present invention, has a useful application in the generation of fixed gases of high thermic values. Coke produced under low temperature carbonization, impregnated with low 70 cost fuel oils, has a special value in generating producer gas of low thermic values, in which the impregnant and the absorbing coke are entirely consumed. Charcoal made by carbonizing wood, has a special value 75 in this invention for kindling purposes when impregnated with inflammable oils, because the charcoal itself is more inflammable than the mineral cokes of harder texture.

In the present invention, in preparing 80 hydrocarbon impregnants, I may adopt the method of carrying the distillation of oils to a degree in which the residual fractionate will be of the right impregnating liquidity, and hardness after the impregnation of the 85 coke and the cooling of the impregnant. In this case, it is economy, to impregnate the coke with the impregnant while it still retains the heat of the distillation process; for in that way economy may be secured 90 in one operation as well as selected characteristics of low, medium or high specific gravity and partial or complete solidity of the absorbed impregnant after its cooling.

The invention comprises the idea of relying upon the capillarity of coke to absorb the lighter solvent constituents in an impregnant thru an indrawing action of the lighter constituents to the center of the coked particles, leaving the heavier and more 100 dense constituents on the exterior of the coked particles. This provides more or less against dripping of impregnants from the coked particles, or a too greasy character of the exterior surfaces of the particles.

The present invention comprises the idea of heating a fuel oil so as to increase its liquidity during its transportation and delivery, or in preparing it for distillation, or gasification, or burning such oils in various 110 devices. It is obvious that the present method of securing definite temperatures for

fuel oil prior to its complete consumption, may be applied in various ways.

It will be understood that my method of giving heavy carbons of different specific gravities, liquefying heatings, has a practical use not only in rendering them more penetrative as impregnants, but also facilitates their atomization in blowing or mechanically spraying into zones of combustion, whether said zones are under atmospheric pressure, or whether they are in enclosures in which the pneumatic pressure is higher than atmospheric pressure. In case of the ultimate burning of the preheated liquid hydrocarbons in enclosed spaces, the heating would always be under more or less pressure. In any case, the preheating would be effected at temperatures that would not decompose and carbonize such parts of the hydrocarbons as may be in immediate contact with heating surfaces of the contaminants containing the hydrocarbons during their heating. The present invention promises some economic results in connection with the utilization of heavy petroleum fractionates and coal-gas-tars, thru their gasification, or direct burning in heating, or in their increased heating in externally fired gas generating retorts.

I apply the principles of the invention in the preparation of a kindling fuel, in which I use charcoal as a basic matrix, the particles of which I impregnate with matters more inflammable than the charcoal, and which impregnants may be varied as to their liquidity of character. Fuel oil to which an addition of pitchy matters in sufficient amounts to thicken the resultant fuel oil, I may admix and liquefy with heat, and use as an impregnant for coke. The heating of the impregnant increases its liquidity, and enables the impregnant to be more quickly and completely absorbed into the porosities of the fuel; and when the impregnant is cooled to atmospheric temperatures, it is then better retained by the rough surfaces of, and in drawing capillary attraction in the porosities of the coke, and hence does not freely exude from the coke particles. In the preparation of a kindling fuel, I prefer to have the impregnant after its cooling, to be of a partly fluid viscous character; because such non-solid impregnant inflames more quickly and transmits a quicker kindling heat to superimposed fuel in its ignition. In the preparation of such fuel, I merely sufficiently liquefy a solid or nearly solid pitch, and dip particles of coke in the liquefied pitch, which mostly adheres to the external surfaces of the coked particles. After the dipping, to prevent adhesion of the dipped particles, the adherent matter is quickly cooled after removal from the liquefied pitch. In burning such coated coke, the coating matter, if in not too thick a coat,

after it is melted under the heat of the burning, is drawn into and retained in the porosities of the coke, and only gradually volatilizes as the coke burns, and without dripping entirely thru the fuel-mass in the burning process.

By using hardened coked particles as a frame or matrix to hold and retain impregnating hydrocarbon fractionates of distillation, I produce a fuel that secures a better draft passing character in a fuel-mass, than is maintained in combinations of soft coal particles bound together in briquette form. In heating impregnants, to avoid the accident of ignition, care must be taken not to overheat them to an inflammable degree. This can be conveniently effected by adding excess air for combustion in the burning of the heating materials. In the present invention, in heating impregnating oils, I may heat them with steam pipes located in the containers in which the impregnants are held and whether the containers are stationary or ambulatory. This practice overcomes the difficulty of handling heavy, viscous oils during cold weather. In some cases I heat and dry the coke with hot air or with hot exhaust gases of combustion, and to a degree higher than would be safe to apply to the impregnating material without controlling the applied heating temperature.

This invention comprises the idea of feeding coked particles of suitable size impregnated with a liquid fuel, onto the upper fuel surface of an internally fired producer gas generator.

In the present application when I use the word "coke," it applies to both coked wood and to coked mineral coals, whether carbonized at high or low temperatures. As recipient impregnating mediums, I prefer for fire kindling purposes, charcoal or coke prepared by low temperature carbonization. Low temperature coke retains a certain amount of volatile, which conduces to its inflammability.

In preparing a kindling fuel of impregnated charcoal, the inflammability of the impregnant may be too great, which defect may be overcome by a redipping of the impregnated particles with a heated pitch that is not of highest inflammable character; or, a selection can be made of an impregnating matter having a higher flash point and a lesser degree of inflammability. The flash point of an impregnant may be so low or so high as to have too great an inflammability, or not enough; or it may have a suitable degree of inflammability. The matter of being able to hold fire in a kindling fuel, is important. As is known, charcoal thru its smoldering character, holds fire for a considerable time; and if in sufficient bulk, it is a good kindling fuel, altho slow in action. I have found it to be of value, to admix im-

pregnated charcoal particles with unimpregnated charcoal particles, and thus secure the dual character of quick ignition and a long continued production of heat for igniting 5 superimposed fuels. This is desirable in connection with the ignition of hard cokes, or hard raw fuels.

What I claim as new is:

1. The method herein described which 10 consists in heating a fractionated hydrocarbon oil of a hardness and density of character that will not run at ordinary atmospheric temperatures when unheated dipping coked fuel particles in the heated fractionate, and cooling the dipped particles.

2. The method herein described which 20 consists in heating a fluid hydrocarbon, mixing and dissolving a solid hydrocarbon with the fluid hydrocarbon, impregnating coke with the admixed hydrocarbons, and coating the impregnated coke with a solidifying coat.

3. The method herein described which 25 consists in impregnating coke with a fluid hydrocarbon, and gasifying the hydrocarbon by subjecting the impregnated coke to gasifying temperatures in a gas producing still or retort.

4. The method herein described, which 30 consists in impregnating coke with a hydrocarbon and subjecting the impregnated coke in a gas producer to heat of a determined temperature and of sufficient intensity to develop a fixed burnable gas from the hydrocarbon, the heat being externally applied to the gas producer.

5. The method herein described, which 40 consists in placing coke particles in a bath of a hydrocarbon liquid of pronounced penetrative character, removing the coke from the bath before complete impregnation of

the particles, and holding the particles until capillary attraction in the porosities of the coke has inwardly withdrawn undesired amounts of the liquid from the exterior surfaces of the particles that would otherwise run from the particles.

6. The method herein described which 45 consists in heating and drying coke and impregnating the heated and dried coke with a liquefied hydrocarbon while in a heated state.

7. A fuel particle of coke having its interior porosities impregnated with a fluid hydrocarbon, and having its exterior surfaces coated with a film of hard non-fluid 55 hydrocarbon.

8. A fuel-mass composed of coke particles impregnated with a hydrocarbon having greater inflammability than the coke, and particles of non-impregnated coke.

9. A fuel composed of coke particles impregnated with a highly penetrative diffusive hydrocarbon liquid in amounts less than can be fully absorbed by the coke particles under the influence of capillary attraction in the coke particles.

10. A fuel-mass of coked particles impregnated with a combustible hydrocarbon, and non-impregnated coked particles.

11. A fuel particle of coke having its interior porosities impregnated with a non-solid, easily inflammable hydrocarbon, and an external thin coat of a solid hydrocarbon liquefied by a solvent or otherwise.

12. The method herein described, which 75 consists in preparing a hydrocarbon oil of a specific definite gravity and penetrative liquidity suited for impregnating a coked fuel particle by heating the oil, and impregnating a coked fuel with the heated oil.

JOSEPH MOSES WARD KITCHEN.
